UNITED STATES PATENT OFFICE.

ANDREW K. MONTGOMERY, OF PHILADELPHIA, PENNSYLVANIA.

STEAM-TRAP.

SPECIFICATION forming part of Letters Patent No. 759,461, dated May 10, 1904.

Application filed March 5, 1904. Serial No. 196,734. (No model.)

To all whom it may concern:

Be it known that I, ANDREW K. MONTGOMERY, a citizen of the United States of America, residing in the city and county of Philadelphia, in the State of Pennsylvania, have invented a certain new and useful Improvement in Steam-Traps, of which the following is a true and exact description, reference being had to the accompanying drawings, which

10 form a part thereof.

My invention relates to a novel construction of steam-trap, preferably used in combination with a steam-separator.

The object of my invention is to provide a 15 device of this kind of simple and efficient operation in which a trap-separator is connected with the steam-conduit, and preferably with a separator-chamber constituting part of said conduit, by two ports, one normally open and 20 provided with a valve held a short distance from its seat by resilient means and the other of contracted area and preferably constantly open. The trap-chamber is provided with a waste-pipe having a valve which normally 25 closes it, and the chamber is also provided with a movable device actuated by the accumulation and discharge of water from the trap-chamber and connected with the valve of the waste-pipe, so as to open the same 30 when the accumulated water reaches a determined amount. The opening of the waste-pipe valve by releasing the pressure in the trap-chamber causes the valve operating on the port connecting the steam-pipe and trap- 35 chamber to close, and said valve will remain closed until after the waste-pipe valve has closed and until the steam entering the trap-chamber through the constantly-open restricted passage has restored a practical equilibrium 40 of pressure between the steam-pipe and the trap-chamber.

In the drawings I have represented a steam separator and trap constructed in accordance with my invention in what I believe to be its 45 most efficient form.

In said drawings, Figure 1 is a side elevation of my device; Fig. 2, a vertical section on the line 2 2 of Fig. 1; Fig. 3, a cross-section on the line 3 3 of Fig. 1, and Fig. 4 50 a cross-section on the line 4 4 of Fig. 2.

A represents the separating-chamber, having the steam-pipe entering it at A' and a steam-pipe leaving it at A'', the chamber A thus constituting a part of the steam-conduit.

B represents the trap-chamber separated 55 from the chamber A by the partition C, in which is formed the port and valve-seat (indicated at C') and which also separates the yoke, (indicated at C'').

D is a steam-conduit of restricted area connecting with the chambers A and B at a and b, as shown.

E is the valve, adapted to close the port C' and having a valve-stem E' with nut E'' at top, between which and the yoke C'' is situated a light spring E'', which normally holds the valve E a slight distance above its seat. The upper part of the wall of the chamber B is constructed to form a bearing, as indicated at B', for a rock-shaft F', from which shaft a 70 lever-arm F'' extends into the chamber B and connects, through a link F'', with a cross-bar or bail F', secured to the top of a bucket F, which is placed below the valve-seated port C', so as to receive any water which enters 75 the chamber B through said port. The rock-shaft F' has attached to one of its outer ends the lever-arm F'', supporting a counterweight F'' and connected by a link F''' with a valve H', working in a valve-casing H, which is situated under a waste-pipe G'', said waste-pipe, as shown, terminating in a siphon G' G, the arm G of which extends into the bucket F, as shown in Fig. 2.

The steam entering the separator-chamber 85 A deposits its condensed water therein, the water finding its way through the port C' into the bucket F, and when a sufficient amount of water is collected in the bucket to overcome the counterbalance F'' the bucket moves 90 down and the lever-arm F'' moves up, opening, through the link F'', the valve H', whereupon the steam-pressure in the chamber B forces the water in the bucket F into the siphon-leg G and through the siphon out of the waste-pipe. The escape of steam is prevented by the lowering of pressure in the chamber B, which causes the valve E to seat itself, and when the weight of water in the bucket F is sufficiently decreased the counterweight re- 100

stores the bucket to normal position and restores the valve H' to its normally closed position. On the closing of the valve H' the steam escaping from chamber A into chamber B through the pipe D gradually restores the pressure in chamber B, and when a practical equilibrium in the two chambers is secured the spring E³ opens the valve E, permitting any accumulated water in the chamber A to flow into the bucket F, the valve remaining open until the bucket is again depressed.

The construction described is given by me as that which I consider best adapted for the work; but it is obviously capable of considerable change and modification without departure from the spirit of my invention.

Having now described my invention, what I claim as new, and desire to secure by Letters Patent, is—

1. In a steam-trap, a steam-conduit in combination with a chamber B, having a port connecting it with the conduit, a valve adapted to close said port, but normally held a short distance from its seat by resilient means, a second port of restricted area connecting the steam-conduit and chamber B, a waste-pipe leading from chamber B, and provided with a normally closed valve, a movable device situated in chamber B, and actuated by the collection in and discharge of water from said chamber, and means for opening the valve in the waste-pipe actuated by said movable device when the water collected in chamber B, reaches a determined amount.

2. In a steam-trap, a separating - chamber forming part of a steam-conduit in combination with a chamber B, having a port connecting it with the separating-chamber, a valve adapted to close said port but normally held a short distance from its seat by resilient means, a second port of restricted area connecting the steam-conduit and chamber B, a waste-pipe

leading from chamber B, and provided with a normally closed valve, a movable device situated in chamber B, and actuated by the collection in and discharge of water from said chamber, and means for opening the valve in the waste-pipe actuated by said movable device when the water collected in chamber B, reaches a determined amount.

3. In a steam-trap, a steam-conduit in combination with a chamber B, having a port connecting it with the conduit, a valve adapted to close said port but normally held a short distance from its seat by resilient means, a second port of restricted area connecting the steam-conduit and chamber B, a bucket F, a lever and counterweight arranged to support bucket F, in chamber B, said bucket being so placed as to receive water passing through the valved port into chamber B, a pipe G, connecting the bottom of bucket F, with a waste-pipe G², and a valve in pipe G², connected and actuated by the movements of the lever supporting the bucket F.

4. In a steam-trap, a separating - chamber forming part of a steam-conduit in combination with a chamber B, having a port connecting it with the separating-chamber, a valve adapted to close said port but normally held a short distance from its seat by resilient means, a second port of restricted area connecting the steam-conduit and chamber B, a bucket F, a lever and counterweight arranged to support bucket F, in chamber B, said bucket being so placed as to receive water passing through the valved port into chamber B, a pipe G, connecting the bottom of bucket F, with a waste-pipe G², and a valve in pipe G², connected and actuated by the movements of the lever supporting the bucket F.
